ALEXANDER M. GOW, OF EDGEWOOD PARK, PENNSYLVANIA, ASSIGNOR, BY MESNE ASSIGNMENTS, TO THE WESTINGHOUSE MACHINE COMPANY, A CORPORATION OF PENNSYLVANIA.

PROCESS OF MAKING GAS.

No. 884,655.

Specification of Letters Patent.

Patented April 14, 1908.

Application filed November 11, 1903, Serial No. 180,652. Renewed September 16, 1907. Serial No. 393,114.

To all whom it may concern:

Be it known that I, ALEXANDER M. Gow, a citizen of the United States, and resident of Edgewood Park, county of Allegheny, State of Pennsylvania, have invented certain new and useful Improvements in Gas-Making Processes, of which the following is a specification.

My invention consists of a new process for the conversion of coal into gas which gas consists of a mixture of gases derived from the hydrocarbons of the coal and water gas derived from the coke resulting from the distillation of the hydrocarbons. In the operation of this process the production of water gas is carried on simultaneously with the production of distilled gas in the same producing chamber and the gases mix immediately upon their formation. The process is an intermittent one and the fuel bed is alternately blown by a blast of air and subjected to the action of steam. The novelty of the process consists in the fact that in its operation the blast is applied to a body of coke derived from the coal in the producing chamber by distillation, while the steam is applied to a body of fuel, adjacent to the body of coke, which is at a lower temperature than the body of coke and is undergoing the process of distillation. The steam thus assists in the liberation of the hydrocarbons from the coal, and furthermore, by superheating the steam a large portion of the heat required for distillation may be carried into the producer by the steam. The very heavy hydrocarbons, which usually condense and form tar and heavy oils are entirely broken up by this process and the gases resulting from this breaking up form large and very important constituents of the gas mixture as withdrawn from the producer. This resultant gas is higher in calorific value than water gas for it contains a large percentage of distilled gas; it is lower in calorific value than illuminating gas as made in retorts, for it contains a large percentage of water gas; at the same time it contains a considerable percentage of "illuminants" derived from the heavy hydrocarbon vapors which ordinarily condense as tar.

The accompanying drawing is a vertical section of the apparatus, parts being shown in elevation for convenience of illustration. The gas producing chamber 1 has located near its bottom end a plunger, 2, operated in a cylinder, 3, by means of a hydraulic piston,

4, operated in a cylinder, 5, by means of water, under pressure, delivered through a pipe, 6. A four way valve, 7, delivers water to either end of the cylinder 5 as desired. A fuel supply pipe, 8, connects into the cylinder 3 at a point above the plunger 2 when that plunger is in its lower position. A coal hopper, 9, is placed at the upper end of the pipe 8. A poker, 10, having teeth, 11, 11, is so arranged that coal may be made to pass down the pipe 8 and into the cylinder 3 when the plunger 2 is down. When the plunger 2 is raised by the operation of the piston 4, the fuel above the plunger 2 is forced into a conical shaped piece, 12. The top of the plunger 2 is convex so that the fuel arches against the conical walls of the piece 12 and does not fall down again when the plunger 2 is lowered. This method and apparatus for feeding a gas producer are subjects of applications for Letters Patent already filed by me. Surrounding the cylinder 3 is a casing, 13, enclosing a space, 14, and through the conical shaped piece 12 are holes, 15, 15, connecting the space 14 with the gas producing chamber 1. A pipe, 16, supplies steam to the space, 14, the amount being controlled by a valve, 17. Encircling the producer are pipes, 18, 18, 18, connected to the producing chamber by pipes, 19, 19, 19, 19. Pipes 18, 18, 18 are connected to a pipe, 20, provided with a regulating valve, 21. Air under pressure is supplied to the pipe 20 by means of a blower, 22, driven by any suitable means.

Near the top of producing chamber 1 is located a gas offtake, 23, connecting into two pipes 24, and 25. The openings from the pipe 23 into pipes 24 and 25 are controlled by water cooled valves, 26 and 27, of ordinary construction. The pipe 24 connects to a regenerative chamber, 28, having located in it the checker bricks, 29, 29, 29, 29. The pipe 25 connects to any suitable form of holder (not shown) for the storage of gas made. Above the checker brick and the regenerative chamber 28 is located the steam boiler, 30, consisting of tubes, enclosed in a shell after the usual manner. The top of the boiler 30 connects to the feed water heater, 35. The pipe, 36, from the feed water heater 35 opens to the atmosphere and is controlled by a valve, 32. From the steam space in the boiler 30 leads the steam pipe, 33, controlled by a valve, 34. The steam pipe 33 discharges steam around

the checker brick in the regenerative chamber. A branch pipe, 38, with valve, 39, is provided from pipe 20 leading into pipe 24 to supply air to the bottom of regenerative chamber 28. Cleaning doors, 40, 40, 40, are provided near the bottom of producing chamber 1 for the removal of ash.

The operation is as follows: The producing chamber 1 is filled with ashes to the top of the conical shaped piece 12. A fire is lighted and coke is charged. The blower 22 is started; valve 27 is closed, valves 21, 26 and 32 are opened, and the mass of fuel blasted with air. Instead, however, of blasting so vigorously as to cause the blast to penetrate the entire fuel bed, the blast is of but moderate pressure, and to insure complete combustion to carbonic acid, a large number of blast twyvers are provided, the purpose being to heat the coke along the walls very much hotter than the fuel in the center of the bed. The hot products of combustion pass by means of pipe 23 through pipe 24 into the regenerative chamber 28. These products of combustion may still contain some combustible gases and to consume these the valve 39 is opened and air admitted to the regenerative chamber 28. The hot, completely consumed gases now pass through the checker brick 29, 29, giving up a portion of their sensible heat. They then pass into the steam boiler 30 where they give up more of their sensible heat and raise steam. They then pass to the feed water heater 35 and by pipe 36 are discharged into the atmosphere. When the fuel bed has been sufficiently heated, a charge of coal is forced into the producing chamber by means of plunger 2. Valves 21, 26, 32 and 39 are now closed and valve 27 is opened. Valves 34 and 17 are opened and steam passes under pressure from boiler 30 around the checker brick 29, 29, in regenerative chamber 28, through pipes 24 and 16 into the space 14 and through holes 15, 15 into the fresh charge of fuel. The steam thus serves as a carrier of heat from the regenerative chamber into the fresh fuel. The steam, because of the position of the holes 15, permeates the mass of fuel passing from the center outward and upon coming in contact with the incandescent coke against the walls of the producer is converted into water gas. At the same time it serves to liberate the hydrocarbons in the fuel and the resultant vapors pass with the steam through the incandescent coke and are broken up into "fixed gases." The heat of the body of coke surrounding the fresh charge of fuel also serves to distil the hydrocarbons. The resultant gas, which is a mixture of water gas and distilled coal gas, passes by way of pipes 23 and 25 to a holder (not shown) or to the plate where it is to be utilized. It is also evident that if it is desired to conserve the sensible heat of the

gas made it may be made to pass through any well known apparatus to absorb its sensible heat and cool it.

When the temperature of the fuel bed has been reduced below the point of economical working steam is shut off by means of the valves 34 and 17. Valve 27 is closed. Blower 22 is started. Valves 21, 26, 32, and 39 are opened and the fuel blown to incandescence again. The products of combustion pass, as before, through regenerative chamber 28, boiler 30, feed water heater 35 and to the atmosphere. When sufficient temperature has been attained in the fuel bed, these valves are closed and the producer is given a fresh charge of fuel by means of the plunger 2. The forcing upward of the fresh charge of fuel crowds out the superincumbent mass of fuel against the walls of the producer. The previous charge of fuel, now partially coked, is forced upward and the entire mass receives an upward and outward agitation that renders it porous but at the same time free from holes and hard spots. Valve 27 is now opened and steam again supplied as before by means of valves 34 and 17. These successive operations of blasting, feeding and steaming are continued at suitable intervals.

It is not claimed that the process of distillation ceases absolutely during the period of blasting. Hydrocarbon vapors and gases are all the time being driven off from the comparatively cold interior portion of the fuel bed. But owing to the admission of steam into the relatively cold interior portion of the fuel bed the rapidity of their liberation is much greater during the period of steaming than during the period of blasting. Furthermore, by supplying an excess of air at a number of points around the exterior portion of the fuel bed, so as to insure as great a production of carbonic acid as possible and a minimum production of carbonic acid, the length of the blast period is greatly reduced. It is desired to heat the exterior portion of the fuel bed to as high a temperature as possible in the shortest time possible in order that a relatively small portion of the volatile constituents of the fuel shall be distilled during the period of blasting. Because of their high thermal value and illuminating properties it is very desirable that they shall, to as great an extent as possible, pass into the volume of gas made. The shorter the blast period and the longer the steaming period, the greater the amount of these desirable distilled gases which will pass to the holder.

It will be seen therefore that among the essential and novel features of this process are the maintenance of the exterior portion of a fuel body at a relatively high temperature; the maintenance of the interior portion of the fuel bed at a relatively lower tem-

perature; and causing the volatile portion of the fuel to be liberated in the relatively cold interior portion and to pass through the relatively hot exterior portion. In practice no difficulty is found in maintaining these conditions. The fuel bed as seen from the top when the producer is opened, shows a center noticeably darker in color than the surrounding portion against the walls. This dark center is the upper end of a column of fuel whose lower end is fresh fuel and which is progressively coked from the bottom to the top. As fast as the fuel in the exterior portion of the fuel bed is consumed its place is supplied by coke derived from the coking central column.

The thickness of the hot exterior portion will depend on the strength of the blast to penetrate the fuel bed and the length of the period of blast. In practice the operator has no trouble in controlling the relative temperatures so that all the carbon of the coal is consumed and nearly all the volatile constituents are conserved to augment the volume of gas made, the loss of volatile constituents during the blasting period being very small.

In the foregoing reference is made to the use of coal only. It will be understood that any carbonaceous fuel, containing a large percentage of volatile constituents may be used instead of coal, or, if desired, coal and such materials may be mixed in suitable proportions. In any case the volatile constituents, excepting of course water, are wholly converted into "fixed gases" as well as the carbon content of the fuel.

The foregoing description of the operation considers the manufacture of gas which, with the exception of a small percentage of carbonic acid, is wholly combustible. Should it be desired to produce a gas in greater volume and of lower calorific value it is evident that producer gas can be made and mixed with the gases evolved during the period of steaming. This process and apparatus lends itself, therefore, to the production of any grade of gas desired from producer gas of low calorific value, containing a large percentage of incombustible nitrogen to a gas of high calorific value containing no nitrogen and but a small percentage of incombustible carbonic acid.

I claim as my invention:—

1. The process of making gas which consists in blowing to incandescence the exterior portion of a body of fuel, forcing fresh fuel into the interior of the body, utilizing the sensible heat of the incandescent fuel in the destructive distillation of the fresh fuel, introducing steam into the interior portion of the body of fuel and causing it to pass, first through the fresh fuel and then through the heated exterior portion of the fuel bed.

2. The process of making gas which con-

sists in successively blowing to incandescence the exterior portion of a body of fuel, utilizing the hot products of combustion so obtained for generating steam, forcing fresh fuel into the interior portion of the body of fuel, utilizing the sensible heat of the surrounding incandescent fuel in the destructive distillation of the fresh fuel, introducing steam into the interior portion of the body of fuel and causing it to pass first through the fresh fuel and then through the heated exterior portion of the fuel bed.

3. The process of making gas, which consists in successively blowing to incandescence the exterior portion of a bed of fuel and absorbing the sensible heat of the products of combustion so obtained in a regenerative chamber, forcing fresh fuel into the interior portion of the body of fuel, utilizing the sensible heat of the surrounding incandescent fuel in the destructive distillation of the fresh fuel, introducing superheated steam into the interior portion of the fuel and causing it to pass first through fresh fuel and then through the heated exterior portion of the fuel bed.

4. The process of making gas which consists in maintaining a body of fuel at a higher temperature in its exterior portion than in its interior portion by delivering to the exterior portion a blast of air and introducing fresh fuel and steam into the interior portion, utilizing the sensible heat of the exterior portion in the destructive distillation of the fresh fuel, causing the steam and the volatile constituents of the fresh fuel to pass from the relatively cold interior portion of the fuel bed through the relatively hot exterior portion.

5. The process of making gas, which consists in blowing air into a body of fuel from a plurality of points located around it in order to heat the body of fuel at its circumference, forcing fuel into the interior of the heated body of fuel, utilizing the sensible heat of the heated fuel in the destructive distillation of the fresh fuel causing steam to enter the body of fuel near the center thereof to pass through the fresh fuel and then through the heated fuel.

6. The process of making gas, which consists in maintaining a body of fuel at a higher temperature at its exterior portion than at its interior, and causing steam to enter the interior portion of the fuel bed and then to pass through the relatively hot exterior portion thereof.

7. The process of making gas, which consists in successively blowing to incandescence the exterior portion of a body of fuel, withdrawing from the hot products of combustion a portion of their sensible heat and discharging the same into the atmosphere, utilizing a portion of the heat of the products of combustion for producing steam, maintain-

ing the interior portion of the fuel body comparatively cold, introducing a portion of the steam generated into the interior of the body of fuel, and causing it to pass first through 5 the central and then through the heated exterior portion thereof.

8. The process of making gas which consists in maintaining a body of fuel at a higher temperature at the exterior portion than 10 at its interior portion and causing a heat laden fluid to enter the interior portion of the fuel bed and then to pass through the relatively hot exterior portion.

9. The process of making gas which consists in maintaining a body of fuel at a higher 15 temperature at its exterior portion than at its interior portion and causing a heat laden but inert fluid to enter the interior of the fuel bed and then to pass through the 20 relatively hot exterior portion.

10. The process of making gas which consists in maintaining a body of fuel at a higher temperature at its exterior portion than at 25 its interior portion and causing a heat laden fluid, which is incapable of supporting combustion, to enter the interior portion of said fuel bed and then to pass through the relatively hot exterior portion.

11. The process of making gas which consists in blowing into incandescence the exterior portion of a body of fuel, forcing fresh fuel into the interior of said heated body, utilizing the sensible heat of the incandes-

cent fuel in the destructive distillation of the fresh fuel, and causing a heat laden fluid, 35 which is inert with reference to the fresh fuel, to enter the body of fuel near its center and to pass first through the fresh fuel and then through the incandescent fuel.

12. The process of making gas which consists in successively blowing into incandescence the exterior portion of a body of fuel, 40 forcing fresh fuel into the interior of the body of fuel, introducing a fluid incapable of supporting combustion into the interior portion 45 of the body of fuel and causing it to pass outward through the heated exterior portion thereof.

13. The process of making gas which consists in blowing into incandescence the exterior portion of a body of fuel, absorbing the 50 sensible heat of the combustion so obtained in a regenerative chamber, forcing fresh fuel into the interior portion of the body of fuel, introducing a heat laden fluid, which is incapable of supporting combustion, into the 55 interior portion of the fuel and causing it to pass, first through the fresh fuel and then through the exterior or heated portion.

Signed at Pittsburg, in the county of Allegheny, and State of Pennsylvania, this 9th day of November, A. D. 1903.

ALEXANDER M. GOW.
